IGNITER

Bruce H. Sage, Altadena, and John McMorris and
Glen W. Miller, Pasadena, Calif., assignors to
the United States of America as represented by
the Secretary of the Navy

Application April 2, 1943, Serial No. 481,653

8 Claims. (Cl. 102—70.2)

1

This invention relates to igniters and more particularly to a novel igniter for powder grains, and the like, which comprises a casing containing an electrically operable squib and an auxiliary charge adapted to be fired by the squib. The new igniter may be made in a simple and compact form and is positive and reliable in operation.

The igniter of our invention may be employed for various purposes but may be used to particular advantage for igniting the powder grain in a rocket motor. It has been proposed heretofore to propel a rocket motor by means of a single grain of powder mounted in the motor body so that the grain burns simultaneously on its external surface and on an internal surface formed by an axial passage in the grain, as disclosed in a copending application of C. C. Lauritsen, Ser. No. 481,644, filed April 2, 1943, now Patent No. 2,464,181. In such rockets, it is desirable to ignite the powder by an igniter at one end of the grain, whereby the blast from the igniter is communicated simultaneously to the internal and external surfaces of the grain.

One object of the present invention, therefore, resides in the provision of a novel igniter for use in motors of the type described, which occupies a relatively small space in the motor body and directs a blast instantaneously in a form suitable for igniting the internal and external surfaces of the grain simultaneously. An igniter made in accordance with my invention comprises a casing for receiving an electrically operable squib, and an auxiliary powder charge compressed in the casing adjacent the squib. The auxiliary charge is preferably in the form of flash powder or black powder, or both, and is arranged to fracture the casing, when fired by the squib, and provide a blast which is directed both radially and endwise with respect to the powder grain.

Another object of the invention is to provide an igniter in which the casing has a hollow boss for receiving the squib and adapted to fit into the axial passage in the grain. In the preferred construction, the boss has longitudinal, external ribs for strengthening it, and the main body of the casing contains the auxiliary charge and is provided with means for spacing the main body from the end of the powder grain to form an annular chamber in the motor through which the blast is communicated to the external surface of the grain.

Still another object of the invention is to provide a novel igniter including a generally cup-shaped casing for receiving the squib and auxili-

2

ary charge, and a closure member for use in compressing the charge in the casing against the squib and which is automatically locked in position upon release of the compressing force.

5 These and other objects of the invention may be better understood by reference to the accompanying drawings, in which

Fig. 1 is a longitudinal sectional view of one form of the new igniter;

10 Fig. 2 is a rear end view of the igniter shown in Fig. 1;

Fig. 3 is a longitudinal sectional view of part of a rocket motor embodying the igniter;

15 Figs. 4 and 5 are sectional and end views, respectively, of a modified form of the igniter;

Fig. 6 is a front end view of still another form of the igniter, and

Fig. 7 is a sectional view on the line 7—7 in Fig. 6.

20 Referring to the drawings, the igniter shown in Figs. 1 and 2 comprises a casing having a main body portion 10 containing a charge of black powder 11. The body 10, as shown, is generally cup-shaped in form and may be spun from a sheet of metal. The black powder 11 is compressed in the main body by a closure disc 12 around which the edges of the body 10 are crimped, as shown at 11a. It will be noted the tighter the crimping is done, the more compressed the black powder will become. In its central portion, the disc 12 is provided with a hollow boss 13 extending outwardly from the disc, the disc and boss being preferably molded from a plastic material, such as cellulose acetate.

25 30 35 An electrically operable squib 14 fits closely in the outer end of the boss 13, and the latter has an opening through which wires 15 extend from the squib for conducting current thereto. The inner end portion of the boss 13 contains a charge of flash powder 16 which is compressed in the boss against the squib 14, and a disc 17 may be placed over the inner end of the boss to separate the powder charges 11 and 16. The boss 13 is provided with longitudinal reinforcing ribs 18

40 45 on its external surface, the ribs 18 merging with ribs 19 integral with the closure disc 12 and extending radially from the boss.

The igniter is adapted for use in a rocket motor (Fig. 3) comprising a hollow cylindrical body 21 which is internally threaded at its front end, as shown at 21a, for connection to a suitable pay load (not shown). Within the motor body is a cylindrical powder grain 22, which may be made of ballistite, having an axial passage 23. On its 50 55 outer cylindrical surface, the grain 22 is provided

with spaced longitudinal ribs 22a which fit closely against the inner wall of the motor body, the ribs 22a serving to support the powder grain in the body 21 with a substantial clearance between the external surface of the grain and the inner wall of the body. Accordingly, the grain has an internal combustion surface, defining the passage 23, and an external combustion surface between the ribs 22a, whereby the grain is adapted to burn simultaneously on both surfaces. Preferably, the grain is formed with radial passages 24 spaced along its length, as disclosed in the above-mentioned application of C. C. Lauritsen, Ser. No. 481,644.

Near its front end, the motor body 21 has a closure disc 25 which may be secured in the body by a sealing compound 26. The disc 25 is spaced from the adjacent end of the powder grain to provide a chamber for receiving the igniter casing 10. As shown, the igniter is mounted at the front end of the powder grain with the hollow boss 13 projecting into the axial passage 23 in the grain and with the wires 15 extending through the passage to a suitable current source (not shown). In this position of the igniter, the radial ribs 19 serve to space the main body of the igniter from the front end of the powder grain and thereby form an annular chamber around the base of the boss 13. The main body 10 is substantially smaller in diameter than the interior of the motor body so as to provide an annular chamber around the body 10. It will be apparent that the annular chamber around the igniter body 10 and around the base of the boss 13 communicates with the external combustion surfaces between the grain ribs 22a and also communicates through the spaces between the ribs 18 and 19 with the axial passage 23 in the grain. As a result, when the squib 14 is energized, it fires the black powder 11 through the flash powder 16, and the resulting blast shatters the igniter casing and is communicated into the grain passage 23 and into the external combustion spaces between the grain ribs 22a. The igniter ribs 18 and 19 serve the dual function of strengthening the hollow boss 13 and directing the blast toward the combustion surfaces on the powder grain.

The igniter shown in Figs. 4 and 5 comprises an electrically operable squib 28 which is seated at one end in a charge of flash powder 29. The squib and the flash powder, in turn, are embedded in a charge of black powder 30 compressed in a generally cylindrical casing 31, the squib and powder charges being sealed in the casing by a closure member 32 around which the edges of the container are crimped, as shown at 31a. In the central portion of the closure disc is an opening through which wires 33 extend to the squib for energizing the same.

In the use of the igniter shown in Figs. 4 and 5, the casing 31 is mounted at one end of the powder grain with the wires 33 extending through the axial passage 23 to the current source (not shown). When the squib 28 is energized, it fires the flash powder 29 which, in turn, fires the black powder 30, the latter producing a blast which is communicated to the internal and external combustion surfaces on the powder grain. Preferably, the powder charges 29 and 30 are compressed in the casing 31 to a substantial pressure by the closure disc 32.

A modified form of the igniter casing is illustrated in Figs. 6 and 7. As there shown, the casing comprises a generally cup-shaped body 35,

the inner wall of which flares outwardly toward the open end of the body, as shown at 36. Preferably, the body is provided on its outer surface with longitudinal reinforcing ribs 37 merging with transverse ribs 37a on the closed end of the body. The body 35 with its external ribs may be molded from a suitable plastic material and is adapted to receive an electrical squib and an auxiliary powder charge similar to those shown in Figs. 2 and 4. In its closed end, the body 35 is formed with a passage 38 through which wiring may extend to the squib.

In assembling the igniter parts in the casing 35, the parts are placed in the casing and the auxiliary powder charge is compressed by forcing a closure disc 39 into the casing. The disc 39 is flexible and may be made of fibre, or the like. When the powder charge has been sufficiently compressed by pressing inwardly on the central portion of the disc 39, the pressure on the disc is released and the latter snaps outwardly at its central portion and is locked by the wedging action of the flared surface 36. The powder charge is thus maintained under adequate pressure in the igniter casing, and the casing is sealed by the disc 39.

While we have described and illustrated three forms of the new igniter, it will be understood that the invention is not limited to these forms but is susceptible of various modifications within its scope. All of the illustrated forms of the igniter afford the advantage of providing a uniform, reproducible action because of their accurately controlled geometrical arrangement, in contrast to the prior forms of igniters employing cloth bags for the igniting charge.

If desired, a suitable substance, such as cement or wax, may be used to hold the squib in position and to seal the wires. While the external ribs 40 on the boss 13 (Fig. 1) increase the strength of the igniter, it will be understood that they serve primarily to support the igniter on the powder grain 22.

We claim:

1. An igniter for powder grains, which comprises a casing having a main body portion and a hollow boss on the body, means on the boss for spacing it from the grain, a squib in the boss, and an auxiliary powder charge compressed in the main body and ignitable by the squib.

2. An igniter for powder grains, which comprises a casing having a main body portion and a hollow boss on the body, ribs on the body extending radially from the boss for strengthening the boss and spacing the body from the powder grain, a squib in the boss, and an auxiliary powder charge compressed in the body and ignitable by the squib.

3. An igniter for powder grains, which comprises a casing having main and closure sections, a hollow boss on the closure section, a squib in the outer end portion of the boss, a charge of black powder in the main section, and a charge of flash powder in the boss between the squib and said first charge, the edges of the main section being crimped over the closure section to compress the charges.

4. An igniter for powder grains, which comprises a casing having a main body portion and a hollow boss on the body, radial ribs on the boss and the body, a squib in the boss, and an auxiliary powder charge compressed in the body and ignitable by the squib.

5. In combination, an igniter for a powder grain comprising a casing adapted to receive a

squib and an auxiliary powder charge, the casing being generally cup-shaped with its inner wall flaring outwardly near the open end of the casing, longitudinal ribs on the casing to separate it from the powder grain, and a flexible closure member fitted closely in said flared portion for compressing the auxiliary charge when flexed and being locked in the casing when returned to normal shape.

6. An igniter for a powder grain comprising a casing having a main body portion and a hollow boss on the body extensible into an axial passage of a powder grain, spacing means on the main body abuttable with one end of the grain to space said body from the grain, a squib located in the boss so as to come within the confines of the powder grain, and an auxiliary powder charge in said main body but distanced from said grain end because of the spacing means and ignitable by the squib.

7. An igniter for powder grains comprising a body section, a boss section, a closure separating said sections, an electric squib in the boss section, a flash powder in the boss section ignitable by the

squib, and a charge of black powder in the body section, the edges of the body section being crimped around the closure to compress the latter charge therein.

5 8. A powder grain igniter consisting of a casing containing an explosive charge, said casing having a passage for the egress of wires leading from a charge-detoner in the casing, and circumferentially separated spacing means on the casing engageable at separated points with an end of a powder grain to be ignited, said spacing means projecting from the casing and distancing the explosive charge from said powder grain.
